STEEL CONSTRUCTION COMPANY, OF PITTSBURGH, PENNSYLVANIA, A CORPORA-
TION OF NEW JERSEY.

STRUCTURE FOR CONCRETE FLOORS OR WALLS

Patented Mar. 2, 1915.

1,130,453.

Specification of Letters Patent.

Filed March 14, 1911. Serial No. 837,088.

To all whom it may concern:

Be it known that I, William Mayo Venable, a citizen of the United States, residing at Pittsburgh, in the county of Allegheny, and State of Pennsylvania, have invented a certain new and useful Improvement in Forms for Concrete Floors or Walls, of which the following is a specification.

The invention relates to forms for supporting concrete floors, slabs or walls. The invention is illustrated as applied for the formation of a floor, but it will be understood that the invention is of broader application and that walls or floors of any angle may be formed, depending upon requirements. The invention has for its primary object the provision of a construction having a capacity for repeated re-use, a construction which is durable and one which may be cheaply handled. It has for its further objects the provision of a construction permitting of the spacing of the floor joists at a greater distance apart than is feasible with the ordinary construction employing wooden sheathing; and a provision of a construction permitting of the prompt removal and re-use of the major portion of the apparatus coming in contact with the concrete, without disturbing the other supporting portions of the apparatus which should be left in place a longer period of time. One embodiment of the invention is illustrated in the accompanying drawings, wherein—

Figure 1 is a perspective view of the form as applied in constructing a floor, and Fig. 2 is a section on the line A—A of Fig. 1.

Referring to the drawings, 1—1 are parallel lines, supported from beneath by studs or by any other desired means permitting of their removal after the floor has been constructed; 2—2—3 are joists extending transversely of the purlins; 3—4—5 are bearing strips lying along the sides of the joists and resting preferably upon the purlins; and 4—4—4 are sheet metal lagging plates.

The lagging plates 4 are all of similar construction and comprise a flat top portion for receiving the concrete, and a dovetailed flange 5 at one edge. The bearing strips 3 are provided with notches or slots 6 into which the flanges 5 extend and fit preferably somewhat loosely, such notches being spaced apart distances such that when the plates are assembled as indicated in Fig. 1, the

edges of the plates which are not provided with flanges overlap the edges of the adjacent plates having flanges (Fig. 2). The upper edges of the bearing strips 3 are spaced below the upper edges of the joists a slight distance, so that the top surfaces of 60 the lagging plates 4 come substantially flush with the top surfaces of the beams 2.

The flanges 5 upon the lagging plates 4 not only stiffen these plates so that the joists 2 may be spaced apart distances greater than 65 would otherwise be possible and permitting of the use of relatively light sheet metal in the lagging plates, but such flanges also serve to hold the plates from displacement. In order to keep the bearing strips 3 from 70 accidental displacement with respect to the beams 2, such strips may be secured in position by means of the nails 7 which are relatively small and light so that the bearing strips may be easily detached from the joists. 75

One of the advantages of the construction resides in the fact that the lagging plates 4 may be removed after the concrete has been in place thereover only a short time, and before the removal of the joists 2. The bearing strips 3 are easily removed from the sides of the joists, and by tilting these bearing strips so that they lie at an angle to the position illustrated, or at right angles thereto, the plates 4 are permitted to drop down, 85 freeing them from the concrete floor which has been formed. This operation does not affect the joists 2 which remain in position and give a very considerable amount of support to the concrete floor. The joists 2 90 and purlins can therefore be left in position as long as may be necessary, while the bearing strips and the lagging plates can be removed to another position and re-used.

A further advantage of the apparatus resides in the fact that it may be very cheaply and easily assembled, and in the fact that the lagging plates may be used indefinitely without appreciable deterioration. Other advantages incident to the structure will be 100 readily apparent to those skilled in the art.

What I claim is:

1. In combination in a form for concrete bodies, a pair of parallel joists removably supported in position, a pair of opposing 105 bearing strips lying removably supported along the inner sides of the joists, and a plurality of stiffened lagging plates with

their ends terminating at the sides of the joists and supported upon the bearing strips, the said plates overlapping at their side edges, and the upper edges of the joists and 5 the upper surfaces of the lagging plates lying at substantially the same level.

2. In combination in a form for flat concrete bodies, a pair of parallel joists, a pair of opposing bearing strips lying along the 10 inner faces of the joists, and a plurality of sheet metal lagging plates with their ends terminating at the sides of the joists and with their upper surfaces in substantial alinement with the upper surfaces of the 15 joists, the said lagging plates being provided along their side edges with downwardly projecting flanges engaging the bearing strips, and one of the bearing strips being notched to engage the flanges and space the plates.

20 3. In combination in a form for flat concrete bodies, a pair of parallel joists, a pair of opposing bearing strips lying along the inner faces of the joists and each provided with a plurality of spaced notches, and a 25 plurality of sheet metal lagging plates with their ends terminating at the sides of the joists and each provided with a flange fitting into the said notches.

4. In combination in a form for flat concrete bodies, a pair of parallel joists, a pair of opposing bearing strips lying along the inner faces of the joists and each provided with a plurality of spaced notches, and a 30 plurality of sheet metal lagging plates with their ends terminating at the sides of the joists and each provided with a flange fitting 35

into the said notches, the said bearing strips having their upper edges below the upper edges of the joists a distance approximately equal to the thickness of the lagging plates. 40

5. In combination in a form for flat concrete bodies, a plurality of purlins, a pair of joists extending transversely of the purlins and supported thereon, a pair of opposing bearing strips lying along the inner faces 45 of the joists and resting upon the purlins and each provided with a plurality of spaced notches, and a plurality of sheet metal lagging plates with their ends terminating at the sides of the joists and each provided 50 with a flange fitting into the said notches.

6. In combination in a form for flat concrete bodies, a plurality of purlins, a pair of joists extending transversely of the purlins and supported thereon, a pair of opposing 55 bearing strips lying along the inner faces of the joists and resting upon the purlins and each provided with a plurality of spaced notches, and a plurality of sheet metal lagging plates with their ends terminating at 60 the sides of the joists and each provided with a flange fitting into the said notches, the said bearing strips being detachably secured to the sides of the joists.

In testimony whereof I have hereunto 65 signed my name in the presence of two subscribed witnesses.

WILLIAM MAYO VENABLE.
